UNITED STATES PATENT OFFICE.

MARK W. DEWEY, OF SYRACUSE, NEW YORK, ASSIGNOR TO THE DEWEY CORPORATION, OF SAME PLACE.

METHOD OF ELECTRIC METAL-WORKING.

SPECIFICATION forming part of Letters Patent No. 408,875, dated August 13, 1889.

Application filed June 3, 1889. Serial No. 312,973. (No model.)

To all whom it may concern:

Be it known that I, MARK W. DEWEY, of Syracuse, in the county of Onondaga, in the State of New York, have invented new and 5 useful Improvements in the Method of Electric Metal-Working, of which the following, taken in connection with the accompanying drawings, is a full, clear, and exact description.

My invention relates to a new method of 10 metal-working, in which both the heating-power of the electric current or currents and magnetism are utilized. The magnetism is for the purpose of creating electric stress or 15 resistance in the metal at the part desired to be heated, and the electric current for heating the part where the resistance is created.

In electric metal-working, particularly in 20 operations appertaining to upsetting, separating, or forming metal bars or plates intermediate of their length into various shapes, an enormous volume of current is required to raise the metal to a sufficient working-temperature, especially when said bars or plates are of large cross-section and offer a very 25 low resistance to the current. On account of the low resistance of the bar it is necessary, in order to locate the heat in the same, to make the other portion of the circuit of very large rod or cable of superior conductivity.

30 This rod or cable is usually made of copper, and because of its expensiveness the current generator or transformer must be located in the immediate neighborhood of the operations. As the heating effect of an electric current 35 in a conductor depends not only upon the volume of the current but also upon the resistance of the conductor, the greater part of the heat of the current will be located in that part of the circuit having the greater resistance.

40 In welding operations the resistance can be more easily attained, as the imperfect contact between the two pieces creates the resistance required; but when a large continuous bar of metal of good conductivity is 45 to be heated intermediate of its length it is necessary, as before stated, to form the other portions of the circuit of conductors of lower conductivity than the bar and generate an immense volume of current in the circuit. A 50 very small increase of resistance in a part of

a low-resistance conductor will aid greatly in developing the heat generated by a current in the conductor at that particular part. Therefore by increasing the resistance by subjecting the part to be heated to magnetism or 55 magnetic stress I am enabled to heat a larger bar with a given current and size of conductors connected to the bar than heretofore; or it is possible to heat a bar of metal with less current and smaller or less expensive conductors than by the usual method. The resistance effect depends of course upon the strength of the magnetism and the arrangement of the poles of the magnet in relation to the bar or blank, which relation in turn depends upon 60 the nature of the metal. Greater effects are found in paramagnetic metals, as iron, nickel, &c.; but good effects are found in diamagnetic metals when the poles of the magnet are arranged in proper relation to the blank of such 65 metal, as hereinafter described.

With iron or nickel the magnetic effect is 70 *nil* when the iron is heated to redness; but the source of magnetism (the magnet) may be removed then or before this temperature is 75 reached, as it has accomplished its purpose by creating stress or resistance, and thereby locating the heat in a part of the blank which may then be heated still more, if desired, for the heat itself has produced the required 80 resistance in the bar, which resistance will be maintained and increased by continuing the supply of current. The magnet is removed when its effect is *nil* or no longer necessary, for the purpose also of relieving it from the 85 intense heat, and removing the obstruction which it would form during the further working or treating of the blank. In some diamagnetic metals the magnetic effect is continued during the entire heating operation to 90 retain the resistance at the part heated, otherwise the part would tend to become cooler upon continuing the application of the current. Again, in order to locate the heat at a particular portion of the metal-bar, the clamps 95 have heretofore been placed at each side of the part and the entire portion of the bar between said clamps has been heated. This is objectionable in many cases, as when the clamps are placed close together, in order to 100

locate the heat in a small portion of the bar that requires a forming, shaping, or other operation, while the current is still flowing and the clamps are in the aforesaid position. This difficulty is obviated by my method, which allows the clamps to be widely separated on the bar, the heat located at any point or points along the said bar between the clamps, the same being, preferably, flexibly connected with the circuit, and permits of free and unhampered working of the heated portion, and, further, the clamps themselves are not overheated.

My invention consists, essentially, in subjecting the entire cross-section of a blank to a magnetic field of uniform strength, and simultaneously therewith passing through the blank, including the said magnetized part, an electric current of sufficient volume to soften the said part, and then working or treating the part as desired; or it consists in subjecting the part of a blank to be worked or otherwise treated to a magnetic field and simultaneously therewith subjecting the blank, including the said part, to the heating action of an electric current of suitable volume flowing in a direction different from the direction of the lines of force in the said magnetic field, and then working or treating the said part as desired; and my invention further consists in subjecting the part of a blank to be worked or otherwise treated to a magnetic field, and simultaneously therewith subjecting the blank, including the said part, to the heating action of an electric current of suitable volume, having its direction at right angles, or substantially at right angles, to the direction of the lines of force in the said magnetic field, and then working or treating the said blank as desired.

In the accompanying drawings, Figure 1 illustrates one of the arrangements for accomplishing the herein-described method, wherein alternating currents are supplied both for magnetizing and heating the bar. Fig. 2 is another form of the same wherein the alternating currents supplied to the magnets are rectified or straightened. Fig. 3 shows a magnet with a laminated core that may be used when alternating currents are employed. Fig. 4 shows the poles of a magnet shaped to correspond to the form of the bar. Fig. 5 shows a permanent magnet applied to a bar; Fig. 6, another arrangement of the magnet in relation to the bar; Fig. 7, an electro-magnetic tongs. Fig. 8 shows the arrangement of a bar having an enlargement to be heated above the temperature of the neighboring portions between the clamps, and Figs. 9 and 10 show two elevations of apparatus for magnetizing a plate.

Referring specifically to the drawings, A in Fig. 1 represents an alternating dynamo, A' and A'' the conductors leading therefrom, including an adjustable resistance B to regulate the current, and the primary coil of an

inductional transformer C. As usual with such apparatus, the primary current is of high tension and small volume, and is transformed by a suitable transformer into a current having opposite qualities—viz., low tension and great volume which flows in the secondary circuit C' of said transformer. The said transformer is in this case the source of the heating-current. D is the bar or blank of metal to be heated and worked, and is connected by suitable clamps c—in this case c and c'—with the terminals of the secondary circuit, which is preferably formed of a flexible conductor or conductors of low resistance. E is an electro-magnet arranged with its poles on opposite sides of the bar at or near the point to be heated. The object in thus arranging the poles of the magnet in relation to the bar is to change the position of the molecules in the bar, so that they will lie in a position different from that in which the current places them. a and a' are the coils of the magnet, and are shown in a shunt-circuit F of the primary circuit. f is an adjustable resistance in the shunt to control the current therein. The upper pole of said magnet and coil a is made adjustable vertically, so that the poles may be separated more or less to admit bars between them of different diameters. Although the poles may come in contact with the bar, better effects are obtained when they do not touch the bar, but are held in close proximity to the same, as shown. By increasing or diminishing the current in the shunt or separating the magnets more or less the resistance may be regulated as desired.

Fig. 2 is the same as Fig. 1, with the following exceptions: The current of the magnet is rectified or straightened in any suitable manner, preferably as shown in patent to Westinghouse, No. 373,035, dated November 8, 1887. G indicates the straightening device. The magnet is supported adjustably in any suitable position in relation to the bar, and may be removed entirely, when desired, by means of the jointed arm b. One of the clamps is stationary, and the other c' movable and flexibly connected with the secondary circuit C', so that if endwise pressure or drawing or pulling is the operation to be performed upon the bar after it is heated it may be accomplished by moving the clamp c' by means of the screw d. It will be obvious that both the transformer C and rectifier G may be dispensed with when a continuous direct heating-current is employed, and also that the magnets may be supplied with current from a separate source from that supplying the heating-current.

Fig. 3 shows an electro-magnet having a laminated core e and a single coil a and bar D in position. It is preferred to have the core laminated or formed of insulated wires when the magnet is energized by alternating currents, so that the core will not become heated.

Fig. 4 shows the magnet provided with pole-pieces *i i'*, shaped to correspond to the form of the bar.

Fig. 5 represents a permanent magnet *H* applied to a bar *D* in place of an electro-magnet. A compound permanent magnet may be employed.

Fig. 6 shows an arrangement of the magnet held with its poles in a plane parallel to the axis of the bar, and in that respect differing from the arrangement shown in the other figures, where the poles of the magnets are at diametrically-opposite sides of the bar. Better effects can be obtained with some metals, especially diamagnetic metals, by this or a similar arrangement, as the molecules are then in a position to offer the greatest resistance to the current.

Fig. 7 shows a pair of tongs provided with coils *a* and *a'*, forming an electro-magnet, and a bar *D* in position between the poles.

Fig. 8 represents a bar or blank *D*, connected with clamps *c* and *c'*, and flexible connections *g g*, so that the bar while in circuit and the current flowing through it may be handled, forged, and worked as desired—operations that could not be effected when held in the apparatus shown in Fig. 2—such as twisting, bending, &c. The said clamps or electrical connections in this case are not rigidly connected with each other, as shown in Fig. 2, but are capable of universal movement independent of each other to allow the blank to be handled and formed in any desired shape while connected with the clamps. The bar, when thus flexibly connected in the circuit, may be held while heated by suitable insulated supports, clamps, or tools, stationary or movable. The figure also represents an enlarged portion *h* of the bar desired to be heated in excess of the other portions of the bar between the clamps in position between the poles of a magnet.

Figs. 9 and 10 represent two views of an elongated electro-magnet for magnetizing a plate to be heated and worked, *l* and *l'* indicating the conductors of the heating-circuit.

It will be obvious that it may be advantageous to employ magnetism in some cases for all forms of electric metal-working, including welding, tempering, &c.

For the sake of simplicity, it will be sufficient for the purpose of this invention to suppose that in all cases magnetizing the conductor causes the same to offer higher resistance to the current, and although it may be ultimately found in some cases to have the opposite effect, yet in all cases said magnetization will localize the heat produced by the current at or near the altered part, and, as is well known, after the heat is once located it will itself offer an increased resistance to the current and rapidly develop itself.

Having described my invention, what I claim as new, and desire to secure by Letters Patent, is—

1. The herein-described method of metal-working, consisting in creating electric stress or resistance in a continuous metal bar or blank by subjecting the blank at or near the part to be worked to magnetism and simultaneously therewith passing through the blank, including the said part, an electric current of sufficient volume to soften the said part, and then bending, shaping, or otherwise working or treating the part. 70

2. The herein-described method of metal-working, consisting in subjecting the blank at or near the part to be worked to the action of a magnetic field and simultaneously therewith subjecting a portion of the blank, including the said part, to the heating action of an electric current of sufficient volume to heat the said part, removing the source of magnetism when its effect is *nil*, and continuing to supply said current until the part is sufficiently softened, and then working or treating the said part as desired. 80

3. The method of metal-working, consisting in creating electric stress or resistance in a metal bar or blank connected in circuit by subjecting the part of a blank to be heated and worked or otherwise treated to magnetism and simultaneously therewith passing through said blank, including the said part, an electric current of suitable volume, and then working or treating the said part as desired. 90

4. The method of metal-working, consisting in subjecting the part of a blank to be worked or otherwise treated to a magnetic field and simultaneously therewith subjecting the blank, including the said part, to the heating action of an electric current of suitable volume flowing in a direction different from the direction of the lines of force in the said magnetic field, and then working or treating the said part as desired. 100

5. The method of metal-working, consisting in subjecting the part of a blank to be worked or otherwise treated to a magnetic field and simultaneously therewith subjecting the blank, including the said part, to the heating action of an electric current of suitable volume, having its direction at right angles, or substantially at right angles, to the direction 110 of the lines of force in the said magnetic field, and then working or treating the said blank as desired. 115

6. The method of metal-working, consisting in subjecting the entire cross-section of a blank at or near the part to be heated and worked or otherwise treated to a magnetic field and simultaneously therewith subjecting the blank, including the said part, to the heating action of an electric current of suitable volume having its direction at right angles, or substantially at right angles, to the direction 120 of the lines of force in the said magnetic field, and then working or treating the said blank as desired. 125

7. The method of metal-working, consisting in creating electric stress or resistance in a

metal bar or blank by subjecting the entire cross-section of a blank to a magnetic field of uniform strength and simultaneously therewith passing through the blank, including the 5 magnetized part, an electric current of sufficient volume to soften the said part, and then working or treating the part as desired.

8. The method of metal-working, consisting in connecting the blank to be heated and 10 worked in a circuit by independent universally-movable connections, passing an electric current through the circuit of sufficient volume to heat or soften the blank, and then moving said connections and handling and 15 working the blank as desired.

9. The method of metal-working, consisting in clamping, by independent universally-movable clamps, the bar or blank of metal at two 20 points, leaving a section of the metal between the clamps, connecting the clamps by flexible low-resistance conductors with the source of heating-current, passing an electric current through the flexible conductors, clamps, and section of metal between them, so as to soften 25 the metal, and then moving said clamps and handling and working or treating the blank as desired.

10. The method of metal-working, consisting in clamping the bar or blank of metal at two 30 points, leaving a section of the metal between the clamps, flexibly connecting the clamps by flexible low-resistance conductors with the

source of heating-current, subjecting the metal between the clamps to magnetism and simultaneously therewith passing an electric current through the flexible conductors, clamps, and section of metal between them, so as to 35 soften the metal, and then handling and working or treating the blank as desired.

11. The method of metal-working, consisting in creating resistance to the electric current 40 in a metal bar or blank at or near the part to be heated and worked, passing an electric current through the bar or blank of sufficient volume to soften the same at the part 45 wherein the resistance is created, and then working the blank as desired.

12. The method of metal-working, consisting in flexibly connecting the bar or blank to be heated and worked in an electric circuit, 50 creating resistance to the electric current in the bar or blank at or near the part to be heated and worked, and passing an electric current through the said bar or blank of sufficient volume to soften the same at the part 55 wherein the resistance is created, and then handling and working the blank as desired.

In testimony whereof I have hereunto signed my name this 31st day of May, 1889.
